CONTROL DEVICE FOR PLURAL FLUID
MOTOR OPERATION

Alex S. Ritter, San Rafael, Calif.

Application December 26, 1947, Serial No. 793,987

5 Claims. (Cl. 60—97)

1

This invention relates to a hydraulic control device or hydraulic switch.

The primary object of the invention is to provide a hydraulic control device in the nature of a hydraulic switch which is capable of selectively directing flow or pressure to selected lines, maintaining the other lines closed with safety and ease of operation.

The features of my invention are:

The provision of a rotary drum type hydraulic switch which, with its cross passages, opens only one avenue of escape or passage for the fluid at one time into a system and maintains the other lines inactive; the provision of a manipulating and actuating mechanism which prevents the application of pressure to the system unless the system is operatively connected to a selected line; the automatic safety of the system through said mechanism which prevents the pressure to break the lines; the selective adaptation of the hydraulic control device for use as an outlet flow control from tanks or the like, and in other adaption as a control for hydraulically operated power devices; and the adaptability of the device for a series of controls in multiple units.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description reference is had to the accompanying drawings for the illustrative embodiment of the invention, wherein:

Fig. 1 is a somewhat diagrammatic view of the application of my device in a system for two hydraulic cylinders.

Fig. 2 is a somewhat diagrammatic sectional view of the device adapted as an outlet control for gasoline or oil tanks and the like.

Fig. 3 is a side view of a modified form of the device with a multiple series of passages through its drum working through a multiple series of outlets on the cylinder.

Fig. 4 is an illustrative embodiment of the device in combination with a tire removing tool and it two hydraulic cylinders.

Fig. 5 is a side view partly in section, of the manual actuating or control element for the device.

In my device a cylinder 6 has a bottom 7 at one

end thereof. The other end of the cylinder is covered by a top plate 8 suitably secured in place and provided with a central bearing hub 9. Inside of the cylinder 6 is a rotatable or rotor drum 11 which is also cylindrical and fits in the inner periphery of the cylinder 6. From the rotor drum 11 extends a central shaft 12 through suitable packing glands 13 in the bearing hub 9 whereby the rotor drum 11 may be turned about its axis in the cylinder 6.

A system of passages is provided in the rotor drum 11. The periphery of the cylinder 6 is also provided with a system of ports arranged at suitable angles to be aligned with the respective passages in the rotor drum 11 according to selectively adjusted positions of the latter. In the illustrative embodiment of my invention herein, I provide a diametrical passage 14 and a pair of substantially arcuate passages 15 and 16 spaced on each side from said diametrical passage, the ends 17, 18, 19 and 21 of which latter are substantially at 45° with respect to the diametrical passage 14. Around the periphery of the cylinder 6 are arranged eight equally spaced ports 22, 23, 24, 25, 26, 27, 28 and 29. The object generally is to rotate the rotor drum 11 in such a manner that its passages in use at the particular operation align with suitable ports, and the ports of the cylinder are connected into a conduit system whereby all pressure or flow can be thus switched according to the adjusted angle or position of the rotor drum 11.

The switching system herein described can be extended to furnish control to a comparatively large number of units to be controlled. An illustration of such extension is shown in Fig. 3 wherein the cylinder is provided with two sets of ports spaced from one another wherein the ports in set A are offset with respect to the ports in set B so that the ports of the first set A are approximately in line with the middle of the distance between the ports of the second set B. The drum in that instance is furnished with another set of passages in the same manner as the first set heretofore described except that the passages are in spaced planes and are also offset 22½° with respect to the previous passages. In such a unit a different control adjustment can be accomplished for each 22½° angle turn of the rotor drum 11 in the cylinder 6.

Another feature of my invention is that no pressure or flow can be put through the passages and into the system of conduits connected to the ports of the cylinder, unless and until the rotor 55 is switched to a position of exact alignment with one of the systems connected to the cylinder. This is accomplished by an actuating element such as the actuating lever 31 which is pivoted on a base 32 and is connected by a link 33 to an actuating lever 34 for actuating the fluid flow

or pump pressure to any of the systems upon the movement of the lever 31 from the position shown in full lines in Fig. 5 to the position shown in broken lines in the same figure. However, the end lever 31 could not be moved into this system operating position unless the adjusting element of the fluid switch is adjusted to an alignment to one of the systems connected to the oil switch. In the present illustration on the end of the drum shaft 12 is an adjusting disc 36 in the periphery of which are a plurality of slits 37. Each slit 37 is of sufficient width to accommodate therein the hand lever 31 in the lowered position. The slits 37 are cut into the disc 36 at such angles and circumferential spacing that when one of the slits 37 is aligned with the hand lever 31, then one of the passages in the drum 11 is suitably aligned with a selected set of ports on the cylinder 6 and thus connected to selected conduits for operation. The disc 36 has markings thereon adjacent to each slit 37 to indicate the connection when the particular slit 37 is aligned with the hand lever 31.

For selection, the operator turns the disc 36 in order to bring the properly marked slit 37 into aligned position with the hand lever 31 and then pulls the lever 31 into the aligned slit to render the system operative through the selected passages of the drum as heretofore described. In order to vary the operation, the lever 31 is lifted out of the slit 37 and another slit 37 is aligned with the hand lever 31 and the actuation is repeated in this second selected position. A spring 38 is provided to pull the hand lever 31 back into inoperative position so that when the operator releases the hand lever 31, it automatically disengages from the disc 36 and shuts off further operation of the device. This renders the operation safe and prevents continuing motion while the operator is away from the machine. The spring 38 is secured on the casing 41 and to the lever 34 for pulling the lever 34 into inoperative position and thereby pushing the hand lever 31 out of the slit 37.

As an illustration of the operation of the fluid switch herein described in Figs. 1, 4 and 5, the use of my fluid switch is shown in connection with two hydraulic plungers utilized in the tire removing device, which is described in detail in my co-pending application, Serial No. 642,323, filed January 19, 1946. The tire removing device denoted in its entirety by the reference numeral 46 has a frame 47 on the top of which is a hydraulic cylinder 48, in which works a piston, the rod 49 of which carries a suitable mechanism 50 for pushing a tire off a rim. The rim is supported on a post 51, which post in turn is mounted on a carriage 52 on the bottom of said frame 47 and is movable in and out so as to carry the rim into and out of the machine. This carriage 52 is operated by another hydraulic plunger device 53. My hydraulic switch and device are mounted on the frame 47 at one side in an out of the way position as indicated by the position of the disc 36 at one side of the machine in Fig. 4. A hydraulic pressure conduit is connected to the cylinder 48 and to the cylinder 53 for the respective operations. The disc 36 is marked at the respective slits "In" and "Up" and "Down" and "Out" respectively to indicate the movement of the post 51 inwardly to operative position, the movement of the pushing device upwardly and away from the tire, the movement of the carriage and post 51 outwardly from the machine, and the downward movement of the pushing device

52. The operation in these various positions will be better understood upon the examination of the system connected to the cylinders as illustrated by the diagram in Fig. 1.

5 When the unit is used for the purpose of operating and controlling hydraulic plungers, the central passage 14 is plugged at least at one end, as indicated by the plug 54, so as to render the diametric passage 14 inoperative and limit the 10 operation to the angular passages 15 and 16. In the vertical cylinder 48 works the piston 56. As shown in Fig. 1, the port 57 on the top of the vertical cylinder 48 is connected by a pipe 58 to the drum cylinder port 24. The bottom port 15 59 of this vertical cylinder 48 is connected by a pipe 61 to the drum cylinder port 28 which is diametrically opposite, namely 180° from the first drum cylinder port 24. The horizontal port carrying hydraulic cylinder 53 has its top port 20 62 connected by a pipe 63 to the drum cylinder port 27 which is about 45° in clockwise direction from the drum cylinder port 28. The bottom port 64 of the horizontal cylinder 53 is connected by a pipe 66 to the drum cylinder port 23 which 25 is diametrically opposite the previous drum cylinder port 27. Drum cylinder ports 25 and 26 at the top of the drum cylinder, are alternate ports located between the top connection port 24 for the vertical cylinder 48 and the top connection 30 port 27 for the horizontal cylinder 53. These alternate power or pressure ports 25 and 26 are connected by pipes 67 and 68 respectively to a pressure delivery pipe or conduit 69 which has a pressure gauge 71 connected thereto to indicate 35 the pressure on the lines. This pressure line 69 is connected to the outlet passage 72 of a gear pump 73 in the pump casing 41. The low pressure drum cylinder ports 22 and 29 are located between the bottom ports 23 and 28 respectively 40 for the working cylinders 53 and 48. Pipes 76 and 77 connect together to a reservoir 78 which in turn is connected by a pipe 79 to the intake passage 81 of said gear pump 73. Between the reservoir 78 and the pressure line 69 is interconnected 45 a pre-adjusted relief valve 82 as a safety measure to bypass extreme dangerous pressure. The gear pump 73 is suitably driven, for instance, as illustrated in Fig. 4, by an electric motor 70 and transmission 75.

50 The gear pump 73 pumps the fluid from the intake passage 81 into the outlet passage 72. Between these passages 81 and 72 is a transverse bypass passage 83 which bypass passage is obstructed at the intake passage 72 by a gate valve 84. 55 This gate valve 84 is pivoted on a fulcrum shaft 86 which extends outwardly and is keyed to the end of the lever 34, heretofore described, so that when the lever 34 is pulled upwardly the gate valve 84 is moved downwardly to uncover the bypass passage 83 and block the pressure or intake passage 72. Thus when the hand lever 31 is out of the disc 36, the gear pump 73 circulates through its own bypass 83 and recirculates the fluid without delivering pressure to the pressure 60 line 69. Whenever the proper alignment of a slit 37 of the disc 36 is accomplished and the hand lever 31 is pulled down and held down in the slit 37, the link 33 is pushed down and the lever 34 is also turned down, lifting the gate valve 65 84 up into the position shown in Fig. 1, blocking the bypass 83 and opening the pressure passage 72, so that the pump 73 delivers the fluid under pressure to the pressure line 69.

70 Thus in the position illustrated in Fig. 1 when the disc 36 is in the "Up" position and the end

75

of the lever 31 is held in the "Up" slit 37, the fluid under pressure passes from the pump to the pressure line 69, then into the alternate pressure intake 68 and to port 26 and then through passage 15 and the outlet port 28 and pipe 61 to the bottom port 59 of the vertical cylinder 48 so as to exert pressure on the piston 56 and lift the piston rod 49 and the device 50 thereon upwardly. As soon as the hand lever 31 is released and pulled up by its spring, the gate valve 84 in the pump is closed and the pump circulates within itself, without any action on the system. Then if the disc 36 is turned to a position where the next slot marked "In" is in alignment with the hand lever 31, and the hand lever 31 is pulled into this "In" slit 37, then the position of the passages 15 and 16 having been shifted 45° in clockwise direction, the alternate intake port 25 is connected to the outlet port 27 and the bottom line 63 connects the pressure to the bottom 62 of the horizontal cylinder 53 and moves the piston therein inwardly. If the disc 36 is rotated another 45° in clockwise direction, and aligns the "Down" slit 37 with the hand lever 31, then the connection is between the alternate intake port 26 of the pressure line to the alternate outlet port 24, and through the pipe 58 to the top of the vertical cylinder 48 to apply pressure for the down movement, while the bottom port 59 and its pipe 61 are connected through the port 28 and passage 16 to the bypass port 22.

Another 45° turn brings the "Out" slit 37 of the disc 36 in alignment with the hand lever 31, and brings the passage 15 into connection between the alternate intake port 25 and delivery port 23 so as to connect pressure to the bottom line 66 and the bottom port 64 of the horizontal cylinder 53. The other passage 16 at this time connects the intake port 27 to the bypass port 29 for bypassing from the top of the cylinder 53 back to the reservoir 78. The alignments are accurate because otherwise the hand lever 31 could not be moved down and the bypass gate valve 84 could not be closed and pressure would not build up in the line 69. Therefore complete safety and facility of operation is provided with easy selection and manipulation.

The form shown in Fig. 2 illustrates an arrangement for another use of the hydraulic switch herein described. In this instance, the arcuate passages 15 and 16 are plugged by plugs 91 so that the only passage in operation is the unplugged diametrical central passage 14. In this instance, pipes 92, 93, 94 and 96 connect respectively to ports 24, 25, 26 and 27 of the drum cylinder 6. These pipes are connected, for instance, to four gasoline or oil tanks in the usual gasoline delivery truck or the like. The other four ports 23, 22, 29 and 28 respectively are connected by four short pipes 97, 98, 99 and 101 respectively to an arcuate chest 102 and to an outlet spout 103. In the position shown in Fig. 2, the intake pipe 96 is connected to the horizontal passage 14 and drains the tank or container connected to the pipe 96. In order to connect the outlet to any one of the other tanks, the drum 11 is rotated, for instance, in a clockwise direction and at each 45° turn it will connect to a different pipe which then drains into the corresponding short pipes and to the outlet at the bottom. In the event of a series of sets of ports as shown in Fig. 3, a similar system of piping would be arranged on the second row of ports but offset 22½° from the system hereto-

fore described so that at each 22½° turn of the drum 6 a different container is connected to an outlet for draining. This allows a quick selection for draining any selected tank, for instance, in a delivery gas truck, where at the present time, complicated valve systems have to be used for the closing and opening of the various tanks.

The device herein described is very easily converted from the actuation of hydraulic plungers as herein described for various purposes where hydraulic plungers may be used. It is adapted to be used with two or more hydraulic plungers according to the need for multiple control. The device is quickly adjustable to selected combinations of positions and is observable and safe. The device can be converted from its use as a hydraulic plunger control to a control for the discharging of multiple tanks or containers, by simply plugging the arcuate passages of the same and leaving the central diametrical passage operative. It might be easily converted into multiple units by added sets of series of offset passages and series of offset ports on the same drum and cylinder as illustrated in Fig. 3. In general the device is highly flexible and adaptable to a variety of uses and a variety of controls; in each case it operates safely and does not require any adjustment excepting the selecting of the operating position and then it automatically accomplishes the control desired.

I claim:

1. A fluid flow control device, comprising a cylindrical casing, a drum rotatable in the casing, a plurality of transverse passages in said drum having their openings on the periphery of said drum, a plurality of ports leading from said cylinder, said openings of said passages and said ports on said cylinder being substantially equally spaced circumferentially for selective alignment of said passages with said ports according to the relative angular position of said drum and said cylinder, and a system of conduits being connected to said ports for conducting the flow through selected drum passages, a fluid pump connected to certain conduits of said system for conveying fluid under pressure, other conduits of said system being connected to the intake of said fluid pump for return flow, a bypass circuit to bypass said fluid under pressure from said pump, a normally open valve adapted to close said bypass circuit, and the remaining ports and conduits being connected to devices operable by said fluid pressure, an adjusting element extended from the drum for adjusting the position of the drum, means on said element to indicate the position of alignment of the respective passages of said drum with respect to the ports of said cylinder, and an actuator member connected to said valve being movable for permitting a buildup of pressure by said pump through said conduit system, said actuator element and said indicator means coacting to allow actuating movement of said member only when said indicating elements indicate an aligned position of said drum passages with respect to ports corresponding to said indication.

2. In a fluid control device of the character described, a cylinder, a plurality of ports on said cylinder being spaced circumferentially substantially at 45° apart, a pair of transverse passages on each half of said drum, the openings of each of said passages being 90° apart from the ends of the other passage, two pairs of diametrically opposite ports being connected to the intakes of hydraulically actuated devices, and the two other diametrically opposite pairs of ports being con-

nected to a fluid pressure circulating system, an adjusting member for adjusting and indicating members on said element for indicating the position of alignment of said drum passages with a set of said ports, a control mechanism for said pressure circulating device normally bypassing said pressure from said system of passages, said mechanism including an actuating element, said actuating element coacting with said indicating means for actuation only when said indicating means are in a position corresponding to an alignment of said drum passages with a set of ports.

3. In a fluid control device of the character described, a cylinder, a plurality of ports on said cylinder being spaced circumferentially substantially at 45° apart, a pair of transverse passages on each half of said drum, the openings of each of said passages being 90° apart from the ends of the other passage, two pairs of diametrically opposite ports being connected to the intakes of hydraulically actuated devices, and the two other diametrically opposite pairs of ports being connected to a fluid pressure circulating system, an adjusting member for adjusting and indicating members on said element for indicating the position of alignment of said drum passages with a set of said parts, a control mechanism for said pressure circulating device normally bypassing said pressure from said system of passages, said mechanism including a handle lever, said indicating member being engageable by said handle lever only in respective selected aligned drum positions.

4. A fluid flow control device, comprising a cylindrical casing, a drum rotatable in the casing, a plurality of transverse passages in said drum having their openings on the periphery of said drum, a plurality of ports leading from said cylinder, said openings of said passages and said ports on said cylinder being substantially equally spaced circumferentially for selective alignment of said passages with said ports according to the relative angular position of said drum and said cylinder, and a system of conduits being connected to said ports for conducting the flow through selected drum passages, a fluid pump connected to certain conduits of said system for conveying fluid under pressure, other conduits of said system being connected to the intake of said fluid pump for return flow, and the remaining ports and conduits being connected to devices

operable by said fluid pressure, said pump having an intake and an outlet, connected into said conduit system, bypass means to bypass pump pressure for said system and to circulate the fluid within the pump, a mechanism for releasing said bypass means at will, and opening the pump outlet to said conduit system, and an actuating element for said mechanism being operable only when the passages of said drum are aligned with selected ports of said system.

5. A fluid flow control device, comprising a cylindrical casing, a drum rotatable in the casing, a plurality of transverse passages in said drum having their openings on the periphery of said drum, a plurality of ports leading from said cylinder, said openings of said passages and said ports on said cylinder being substantially equally spaced circumferentially for selective alignment of said passages with said ports according to the relative angular position of said drum and said cylinder, an adjusting disc for turning said drum relatively to said cylinder, said disc having circumferential slits spaced apart at the same circumferential angle as the position of said operating ports, a normally open pump bypass passage to bypass the fluid flow, a bypass valve adapted to close said bypass passage and to direct fluid flow under pressure to said cylinder, and a valve operating element abutting against the periphery of said disc except when one of said slits is aligned therewith and operating said bypass valve to close said passage when said element is depressed into said aligned slit.
